(57) **CLAIM**

The ornamental design for a removable cartridge for a diffusion device, as shown and described.

DESCRIPTION

FIG. 1 is an isometric view of a removable cartridge for a diffusion device showing our new design.

FIG. 2 is an isometric view thereof from another viewpoint. FIG. 3 is a front elevational view thereof, which is the same as each of the rear elevational view, the right side elevational view and the left side elevational view.

FIG. 4 is a top plan view thereof; and,

FIG. 5 is a bottom plan view thereof.

Stippling shown in the drawings is intended to represent the approximate three-dimensional contours of the design, and is not intended to indicate surface decoration. The broken lines in the figures form no part of the claimed design.
